Alfred C. Kather
INVENTOR.

UNITED STATES PATENT OFFICE

141,209

DESIGN FOR A PROPELLER BLADE

Alfred C. Kather, Sioux City, Iowa

Application January 12, 1943, Serial No. 109,491

Term of patent 7 years

(Cl. D71--1)

To all whom it may concern:

Be it known that I, Alfred C. Kather, a citizen of the United States, residing at Sioux City, in the county of Woodbury and State of Iowa, have invented a new, original, and ornamental Design for Propeller Blade, of which the following is a specification, reference being had to the accompanying drawing forming part thereof.

Figure 1, in the drawing, is a front perspective view of a propeller blade showing my new design.

Figure 2 is a rear perspective view of a propeller blade showing my new design.

I claim:

The ornamental design for a propeller blade, as shown.

ALFRED C. KATHER.
